ATTORNEY

UNITED STATES PATENT OFFICE

IRVING S. BODKIN, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed October 13, 1930. Serial No. 488,485.

The present invention relates to that class of safety razors in which two clamping members, a guard member and a blade backing member are provided, and a thin flexible 5 blade is flexed and clamped between the guard and backing members to retain the cutting edges of the blade in shaving relation to the guard teeth.

In razors of the type mentioned one of the 10 blade clamping elements, the blade backing member, is provided with a screw-threaded clamping pin which is adapted to be extended through the blade and through a hole in the guard member, for engagement 15 with a screw-threaded bore in the handle of the holder, said pin and handle serving to bring the blade clamping elements into proper relation for shaving. Therefore, when a used blade is to be replaced, it is 20 necessary to disengage the handle from the clamping pin, that is to say the holder must be taken apart with the consequent liability of dropping or losing parts, which is an 25 objectionable feature of devices of this character.

The main object of the present invention is to provide a blade holder and blade construction whereby the elements of the razor 30 need not be taken apart for the purpose of either replacing a blade or for cleaning the elements.

With these and other objects in view, which will more fully appear as the nature 35 of the invention is better understood, the same consists in the combination, arrangement and construction of parts hereinafter described, pointed out in the appended claims and illustrated in the accompanying drawing, it being understood that many 40 changes may be made in the size and proportion of the several parts and details of construction within the scope of the appended claims, without departing from the spirit or sacrificing any of the advantages 45 of the invention.

Two of the many possible embodiments of the invention are illustrated in the accompanying drawing, in which:

Figure 1 is an end view of a razor constructed in accordance with the present in-

vention; Fig. 2 is a section taken on line 2-2 of Fig. 1; Fig. 3 is a section taken on line 3-3 of Fig. 2, part of the blade backing member being shown in elevation to properly illustrate the relation of the 55 elements; Fig. 4 is a section taken on line 4-4 of Fig. 2; Fig. 5 is a top plan view of the guard member of the construction; Fig. 6 is a bottom plan view of the blade backing member; Fig. 7 is a plan view of the improved blade; Fig. 8 is a bottom plan view of a modified blade backing member and a modified blade in position thereon and Fig. 9 is an end view of the modification of Fig. 8 with the parts assembled. 60

Referring now first to Figs. 1 to 7, inclusive, of the drawing, the numeral 10 indicates the guard member, the numeral 11 the blade, and the numeral 12 the blade backing member of the razor, so organized that 70 the said blade may be clamped between said members. The guard member is shown of the variety having guard teeth 13 in its opposite longitudinal edges, along which the cutting edges 14 of the blade may extend in 75 an ordinary way for shaving. Any suitable means may be provided for causing the blade to be clamped between the guard and backing members. In the example illustrated in the drawing, the backing member 80 is provided with a centrally arranged screw-threaded pin 15, which is adapted to pass through an aperture 16 in the blade and through an opening 17 in the guard member, and to engage a screw-threaded socket 85 18 in a handle 19, to clamp the parts together for shaving.

The aperture 16 is, generally speaking, in the form of a central longitudinal slot, which extends from one of the transverse 90 edges of the blade, denoted by the numeral 20, toward the other transverse edge, but stops short of the latter. This slot is provided with a central transverse enlargement 21, through which the clamping pin 15 is 95 adapted to pass. The said slot is furthermore provided on either side of the said central enlargement with a transverse enlargement 22, the last-mentioned enlargements being disposed adjacent the ends of 100

the slot and being adapted to take each a cylindrical positioning-stud of the blade holders of the ordinary Gillette type of safety razors. In each corner of the blade 5 is formed a re-entrant recess 23, for a purpose hereinafter to be described. The blade aperture 16 is adapted to receive a non-cylindrical positioning stud 24, in the form of a rib, extending from the blade engaging 10 face of the backing member 12 and being arranged in the longitudinal center line of the latter. This rib is uninterrupted throughout its length, the pin 15 projecting from the free edge 25 thereof (see Fig. 4). 15 The rib is adapted to enter a groove 26 in the longitudinal center line of the guard member 10, thereby positioning the blade and clamping member in relation to the guard teeth. 20 Adjacent one of the transverse edges of the blade backing member 12 extend from the blade engaging face of the latter two projections 27, they being located at the intersection of the said transverse edge with 25 the two longitudinal edges of the blade backing member, that is to say at the corners thereof. These projections fit and enter the re-entrant recesses 23 in the blade at that transverse edge thereof into which 30 the blade slot opens, and serve to prevent spreading of the blade when the latter is clamped in the holder, as will hereinafter more fully appear. In the opposite transverse edge of the blade backing member 12 35 is formed a notch 28, adapted to register with a notch 29 in the guard member, to permit grasping of the blade when the latter is to be removed from the holder.

In Figs. 1 to 4, inclusive, of the drawing 40 the elements of the razor are shown assembled for use. The projections 27 on the blade backing member are seated in those two re-entrant recesses 23 of the blade which are adjacent the open end of the blade slot 45 and thereby prevent spreading of the blade as the latter is clamped between the guard and backing members. When the blade is to be removed from the holder, the handle 19 is unscrewed from the clamping pin 15 50 to an extent that the guard and backing members are separated to release the blade; more particularly until the blade flattens out. The blade is then grasped between two fingers inserted into the registering 55 notches 28 and 29 in the blade backing member and guard member, respectively, and drawn longitudinally of the holder until the rib 24 is disengaged from the blade slot, when it may be readily removed from 60 the holder. A new blade may then be inserted by bringing the open end of the slot therein into alignment with the rib on the blade backing member and shifting the blade longitudinally on the holder until 65 stopped by the slot end abutting against

the respective rib end. The handle is then screwed down, whereby the blade is properly flexed and clamped between the guard and backing members. From the foregoing it will be seen that the blades may be mounted upon and taken off the blade clamping members and that the safety razor may be efficiently cleaned without the necessity of taking the device to pieces.

Attention is called to the fact that for 75 the proper co-operation of the razor elements, re-entrant recesses need be formed only in that end of the blade in which the blade slot terminates. The re-entrant recesses shown in the drawing on the opposite 80 blade end are provided only in order to obtain a symmetrical blade. This is, however, not necessary as appears from the construction illustrated in Fig. 8 of the drawing, in which only in one blade end are provided recesses 30, for co-operation with pin-like 85 projections 31 on the blade backing member 32. The operation of the device shown in Fig. 8 will be readily understood from the foregoing 90 description.

It is obvious that, while herein the positioning stud, that is the rib 24 has been described as being located on the backing member and the groove 26 has been specified as being formed in the guard member, the 95 relative positions of these elements may be reversed without departing from the invention, which lies mainly in the provision of a construction wherein an open slotted blade may be mounted upon and removed from the holder without taking apart the elements of the latter. As far as the gist of the invention is concerned, it is immaterial 100 whether the means for preventing spreading of the blade are located on the blade backing member, as herein described, or on the guard member. It is also obvious that, instead of the specific positioning stud herein referred to, one or more studs of other forms may be used on the holder for co-operation with the blade slot.

What I claim is:—

1. A safety razor, comprising blade clamping members, a blade having transverse edges adapted to fit between said members, multiple means to clamp said members on said blade, said blade having a central longitudinal slot opening into one of its transverse edges, a blade positioning rib extending longitudinally of one of said clamping members adapted to enter said slot and permitting the blade to be shifted longitudinally between said blade clamping members while the elements of said clamping means are in engagement with one another, said blade being provided with recesses in that transverse edge thereof into which said slot opens, and projections on one of said clamping members adapted to 110

- be seated in said recesses to prevent spreading of the blade at its open slot portion when said clamping members are being clamped thereon.
5. 2. A safety razor, comprising blade clamping members, a blade having transverse edges adapted to fit between said members, multiple means to clamp said members on said blade, said blade having a central longitudinal slot opening into one of its transverse edges, a blade positioning rib extending longitudinally on one of said clamping members, the other clamping member being provided with a longitudinal groove 10 into which said rib is adapted to fit, said rib being adapted to enter said blade slot and permitting the blade to be shifted longitudinally between said blade clamping members while the elements of said clamping 15 means are in engagement with one another, said blade being provided with recesses in that transverse edge thereof into which said slot opens, and projections on one of said clamping members adapted to be seated in 20 said recesses to prevent spreading of the blade at its open slot portion when said clamping members are being clamped thereon.
3. A safety razor, comprising a backing member, a razor blade having transverse edges adapted to be held thereon, said blade having a central longitudinal slot opening into one of its transverse edges, a positioning rib on said backing member adapted to 25 enter said slot, a guard member having a longitudinal groove to receive said positioning rib, and means for retaining the backing member, blade and guard member in assembled relation to one another, said rib being adapted to enter said slot and permitting the blade to be shifted longitudinally 30 between said backing and guard members without disengaging said retaining means, said blade being provided with recesses in that transverse edge thereof into which said slot opens, and projections on one of said clamping members adapted to be seated in 35 said recesses to prevent spreading of the blade at its open slot portion when said backing and guard members are being clamped on said blade.
4. A safety razor, comprising blade clamping members, a blade having transverse edges adapted to fit between said members, multiple means to clamp said members on said blade, said blade having a central longitudinal slot opening into one of its transverse edges, blade positioning means on one of said clamping members adapted to enter said 40 slot and permitting the blade to be shifted longitudinally between said blade clamping members while the elements of the said clamping means are in engagement with one another, said blade being provided with recesses in that transverse edge thereof into 45 which said slot opens, and projections on one of said clamping members adapted to be seated in said recesses to prevent spreading of the blade at its open slot portion when said clamped thereon.
5. A safety razor blade having transverse edges adapted to be flexed transversely by the clamping action of a holder and comprising two cutting edge portions separated 50 longitudinally by a slot which opens into one of the transverse edges of the blade, said blade being provided with recesses in that transverse edge portion thereof into which said slot opens to take projections on the holder to prevent spreading of the open slotted portion of the blade when the latter is being clamped in a holder.
6. A safety razor, comprising a backing member, a razor blade having transverse edges adapted to be held thereon, said blade having a central longitudinal slot opening into one of its transverse edges, a positioning rib on said backing member adapted to enter said slot, a guard member having a longitudinal groove to receive said positioning rib, and means for retaining the backing member, blade and guard member in assembled relation to one another, said rib being adapted to enter said slot and permitting the blade to be shifted longitudinally 55 between said backing and guard members without disengaging said retaining means, said blade being provided with re-entrant recesses in that transverse edge thereof into which said slot opens, and projections on said backing member adapted to be seated in said recesses to prevent spreading of the blade at its open slot portion when said backing and guard members are being clamped on said blade.
7. A safety razor, comprising a guard member, a backing member adjustable with relation to said guard member, a guide intermediate the backing and guard members, a blade slidable on said guide longitudinally of said backing and guard members, and means intermediate the backing and guard members for holding a blade against lateral distortion.
8. A safety razor, comprising a guard member, a backing member adjustable with relation to said guard member, a guide intermediate said backing and guard members, a partially split blade slidable on said guide longitudinally of said backing and guard members, and projections on the under face of said backing member overhanging the blade to hold the split end of the latter against lateral distortion.
